DESIGN FOR AN ELECTRIC POWER DRIVE UNIT FOR USE WITH HAND CUTTING TOOLS

William A. Phllis, Warren, Ohio, assignor to
Beaver Pipe Tools, Inc., Warren, Ohio, a cor-
poration of Ohio

Application July 20, 1939, Serial No. 86,131

Term of patent 14 years

To all whom it may concern:

Be it known that I, William A. Phllis, a citizen of the United States of America, residing at Warren, in the county of Trumbull and State of Ohio, have invented a new, original, and ornamental Design for an Electric Power Drive Unit for use with Hand Cutting Tools, of which the following is a specification, reference being had to the accompanying drawing, forming part thereof.

In the drawing, Fig. 1 is a perspective view of an end and one side of the electric power drive unit for use with hand cutting tools, embodying my new design; Fig. 2 is a perspective view of the other end and side thereof.

I claim:

The ornamental design for an electric power drive unit for use with hand cutting tools, sub-stantially as shown.

WILLIAM A. PHILLIS.
